UNITED STATES PATENT OFFICE.

GOTTLIEB LOEWENSTEIN, OF BRUNSWICK, GEORGIA.

CURTAIN-POLE HANGER.

SPECIFICATION forming part of Letters Patent No. 688,425, dated December 10, 1901.

Application filed July 22, 1901. Serial No. 69,291. (No model.)

To all whom it may concern:

Be it known that I, GOTTLIEB LOEWENSTEIN, a citizen of the United States, residing at Brunswick, in the county of Glynn and State of Georgia, have invented certain new and useful Improvements in Curtain-Pole Hangers; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to a device for putting up and taking down curtain-poles from which are suspended lace curtains or other draperies, and for convenience I will designate the same as a "curtain-pole hanger."

20 The invention has for its object to provide such a device which when not in use can be folded or telescoped so as to occupy but little space and which when to be used may be extended so as to increase its length and in which the several parts will assume a position constituting a fork adapted to receive and grasp the curtain-pole at two different points, so that it may be steadied and supported in lifting it into place and taking it therefrom.

25 To the accomplishment of the foregoing and such other objects as may hereinafter appear the invention consists in the construction and in the combination of parts herein-after particularly described and then sought 30 to be clearly defined by the claims, reference being had to the accompanying drawings, forming a part hereof, and in which—

Figure 1 is an elevation of the device with the parts in their closed or telescoped position, the staff being broken in two to shorten the parts for purposes of illustration. Fig. 40 2 is a top end view of the parts closed. Fig. 3 is a vertical section through the hollow staff with the other parts in full lines and in their closed position. Fig. 4 is an elevation 45 of the parts in position for operation with the staff broken in two and the coiled spring in dotted lines. Fig. 5 is an elevation at right angles to Fig. 4. Fig. 6 is an elevation showing the parts in position in the operation of closing. Fig. 7 is an elevation showing the parts nearly closed into the hollow staff, and

Fig. 8 is a side view of an elbow adapted to fit over the end of the device when used for dusting or cleaning walls or windows. 55

In the drawings the numeral 1 designates a hollow or tubular staff made of metal or other suitable material, which may be closed at one end by means of a plug 2, formed of wood or other material. Within the staff fits 60 a sliding shank 3, between which and the plug 2 is located a spiral or coiled spring 4, adapted to project the shank 3 so as to have the same extend through the open end of the tube 1 when the parts are to be placed in position for operation. The shank 3 has hinged to its upper end two arms 5, which hinge may be formed by the two leaf members 6, connected by a pintle 7 to a plate 8, which may fit in the end of the shank 3 and be secured thereto by rivets 9 or otherwise. The arms 5 when spread apart form a fork which will be held in its open position by a flexible spring 10, secured rigidly at one end to one of the arms and having its other end passing 65 through a loop 11, attached to the other arm, so that it may move freely through the loop, said spring when the two arms are spread apart assuming substantially the position shown in Fig. 4, so as to hold the arms apart, 70 and when the arms are brought together said spring will slide in the loop 11, so as to permit the arms to be brought together, and when brought together the loop 11 will fit in a recess 12, formed in the other arm, so that 75 the arms, together with the shank, may be moved down into or telescoped into the staff 80 1, as illustrated in Fig. 3 of the drawings.

Each arm 5 toward its outer end has hinged to it an arm or tine 13, which is adapted to fold 90 against the arm 5 when the device is to be closed or telescoped and to swing outward from the arm 5 when the device is to be used, so as to form a fork adapted to receive the curtain-pole, as indicated in Fig. 5 of the 95 drawings, one prong of the fork being formed by the tine 13 and the other by the portion of the arm 5 next thereto, the two arms 5 thus being formed each with a fork at its outer end, so as to receive the curtain-pole, 100 as indicated in Figs. 4 and 5 of the drawings. A portion of the outer end of each arm 5 may be cut away, so as to permit the tine or prong 13 to form a close joint with the arm

5 when the prong or tine is pressed toward the same, so that when the arms 5 are brought together and the prongs 13 are folded against the reduced portion of the arm the diameter 5 of the parts will be substantially of the same diameter as the interior of the tubular staff 1, as indicated in Fig. 2 of the drawings. The hinge for connecting the prongs 13 to the arm 5 may consist of a leaf 14, having a pintle 15 journaled in the metal plates 16, riveted to the arms 5, although the prongs may be otherwise hinged thereto. A suitable spring 17 is employed to hold each prong 13 spread from its arm 5 when the parts are in operative position, 15 which springs will be compressed when the prongs 13 are closed, so that the parts may slide or telescope within the tubular staff 1. When the parts are telescoped into the staff 1, the coiled spring 4 is compressed, and the shank 3 and its forks are held within the staff against the pressure of the coiled spring by means of spring-fingers 18, suitably secured to the tubular staff near its outer end, said fingers having their hook ends fitting over 20 the outer ends of the arms 5 and prongs 13, as illustrated in Figs. 1, 2, and 3, so as to hold the parts in their telescoped position, the fingers 18 being held in their clamping position by means of a ring 20, adapted to slide so as 25 to compress the fingers, and thus hold them in place over the ends of the parts when telescoped, as illustrated. These fingers also serve to hold the shank 3 and its arms in position for lifting and lowering the curtain-pole, and for that purpose the shank 3 is formed toward its lower end with a circumferential groove 21, in which will fit the hook ends of the springs 18, as illustrated in Fig. 30 4 of the drawings, said spring-fingers being retained in their compressed holding position by means of the ring 20, as illustrated. The upper and lower walls of the groove 21 constitute shoulders against which the springs 18 will bear, so as to hold the shank 3 and its 35 connected parts in operative position, thus preventing the shank from being pushed down in the tubular shaft and also from being pulled entirely out of the same when the device is being used for placing the curtain-poles in position or removing them therefrom. When the parts are to be telescoped, the ring 20 is slid down, whereupon the spring-fingers release the shank 3 and permit it to be telescoped within the tubular staff, and when that 40 is done the fingers 18 serve to hold the parts within the staff, as before described. Upon releasing the grip of the ring 20 on the spring-fingers 18 a coiled spring 4 will eject the shank 3 and its connected parts far enough to enable 45 them to be grasped by the hand, so as to draw them into the position indicated in Fig. 4 of the drawings, and when in that position the spring-fingers, together with the sliding ring 20, will hold the parts in their extended position.

When the device is to be used for dusting walls or cleaning windows, an elbow 22,

formed with bristles or a mop 23, is fitted over the outer ends of the arms 5 and prongs 13, which elbow can be fitted with either of its 70 elbow ends over the end of the device, so as to present the bristles or mop either sidewise or from the top face of the elbow, as will be obvious. This elbow, fitted over the ends of the arms, and the prongs will hold the parts 75 closed against the influence of the springs 10 and 17, as will be apparent.

The device constructed substantially as described is simple in its several parts, comparatively inexpensive to construct, and its 80 several parts are simply and readily brought into operative position and when not in use are telescoped, so that the device can be set aside and occupy but little space and without danger of any of its parts being damaged. 85

I have illustrated and described what I consider to be the preferred details of construction and arrangement of the several parts of the device, but it is obvious that changes can be made therein and essential features of my 90 invention be retained.

Having described my invention and set forth its merits, what I claim is—

1. The curtain-pole hanger or adjuster consisting of the tubular staff, the shank telescoping into the staff, the arms hinged to the shank and adapted to close and lie within the staff, and the prongs hinged to said arms so as to spread apart from the arms and form a fork at the upper end of each of the arms, 95 substantially as described.

2. The curtain-pole hanger or adjuster consisting of the staff, the shank supported by the staff, the hinged arms connected to the shank, the spreading-spring secured to one 105 arm and having one end loosely connected to the other arm holding said arms apart from each other, and forks at the outer ends of said arms to receive the curtain-pole, substantially as described. 110

3. The curtain-pole hanger or adjuster consisting of the tubular staff, a shank slidable in said staff, arms hinged to said shank, and prongs hinged to said arms toward their outer ends, said prongs opening at right angles to 115 the spread of the hinged arms, substantially as described.

4. The curtain-pole hanger or adjuster consisting of a shank, arms hinged to the shank, a spreading-spring between the arms to hold them spread apart, and spring-influenced prongs secured to the arms toward their outer ends, said prongs opening at right angles to the spread of the arms, substantially as described. 120

5. The curtain-pole hanger or adjuster consisting of the tubular staff, the shank slidable within the staff and provided with hinged arms to constitute a fork, a spring within the staff beneath the slidable shank, and compressible fingers for holding the shank and its arms telescoped within the staff, substantially as described. 125

6. The curtain-pole hanger or adjuster con-

sisting of the tubular staff, the shank slidable within the staff and provided with hinged arms constituting the fork, said shank having a circumferential shoulder, and spring-
5 fingers secured to the staff and adapted to be compressed and held against the circumferential shoulder of the shank for the purpose of holding the shank in position, substantially as described.

10 7. The curtain-pole hanger or adjuster consisting of the tubular staff, a spiral spring therein, a shank slidable within the staff and provided with hinged arms carrying spring-influenced forks at their outer ends, a spreading-spring between the hinged arms, compressible spring-fingers attached to the staff
15

and adapted to engage a part of the shank, and a slidable ring for compressing said fingers, substantially as described.

8. The combination of the hollow staff, the shank telescoping into the staff, the arms hinged to the shank, the prongs hinged to the arms, and the elbow to fit over the ends of the arms and their prongs to hold the arms and prongs closed when extended beyond the tubular shank, substantially as described.

In testimony whereof I affix my signature in presence of two witnesses.

GOTTLIEB LOEWENSTEIN.
